US00D801915S

(12) **United States Design Patent** (10) **Patent No.:** **US D801,915 S**
Bauer et al. (45) **Date of Patent:** **** Nov. 7, 2017**

(54) **MOUNTING BRACKET FOR ROOF MOUNTED PHOTOVOLTAIC MODULES**

(71) Applicant: **Unirac Inc.**, Albuquerque, NM (US)

(72) Inventors: **Steve Bauer**, Albuquerque, NM (US); **Bill Vaught**, Albuquerque, NM (US); **Kim Weaver**, Edgewood, NM (US); **Caitlin Purigraski**, Albuquerque, NM (US); **Stacy Harris**, Albuquerque, NM (US); **Charles Stubbs**, Tijeras, NM (US)

(73) Assignee: **Unirac Inc.**, Albuquerque, NM (US)

(**) Term: **15 Years**

(21) Appl. No.: **29/571,281**

(22) Filed: **Jul. 15, 2016**

Related U.S. Application Data

(63) Continuation of application No. 15/192,173, filed on Jun. 24, 2016.
